[57] CLAIM

The ornamental design for a faucet, as shown and described.

DESCRIPTION

FIG. 1 is a top, front, left-side perspective view of a faucet showing my new design;

FIG. 2 is a front elevational view thereof;

FIG. 3 is a rear elevational view thereof;

FIG. 4 is a top plan view thereof;

FIG. 5 is a bottom view thereof; and,

FIG. 6 is a left side elevational view thereof, the right side elevational view being mirror symmetrical thereto.
